UNITED STATES PATENT OFFICE.

JAMES MARSHALL, OF FALL RIVER, MASSACHUSETTS.

AUTOMATIC DYEING APPARATUS.

SPECIFICATION forming part of Letters Patent No. 757,478, dated April 19, 1904.

Application filed January 7, 1904. Serial No. 188,081. (No model.)

To all whom it may concern:

Be it known that I, JAMES MARSHALL, a citizen of the United States, residing at Fall River, in the county of Bristol and State of Massachusetts, have invented a new and useful Automatic Dyeing Apparatus, of which the following is a specification.

My invention relates to improvements in dyeing-vats holding a quantity of dye liquor in which the materials to be dyed are placed and generally stirred with a fork or pole by an attendant, the process requiring open vats from which the steam and dye fumes are obnoxiously escaping and which is dependent for uniform penetration and admixture of the dye upon the skill and faithfulness of the attendant.

The object of my invention is not only to do away with the attendant, but to perform the operation in a much more thorough and uniform manner without damage to the materials and in a closed vat from which the steam and fumes may be led away through a flue; also, to keep the various lots of similar materials being treated for the same color separate, as is often desirable, and now requires separate operations. I attain these objects by the mechanism illustrated in the accompanying drawings, in which—

30 Figure 1 is a side elevation of the apparatus with the cap removed. Fig. 2 is a plan view of the same. Fig. 3 is an end elevation with the cap in position. Fig. 4 is a cross-section through the apparatus on line A.

35 In all the figures like numerals relate to like parts.

1 is a base-frame sustaining the semicircular vat 2. A shaft 3 is attached to one side of the frame, having at one end a driving-wheel 4, 40 to which power is communicated by the belt 5 from a motor-shaft 6. At the other end of the shaft 3, which is journaled in suitable boxes, is a pinion-gear 7, (see Figs. 2 and 3,) which meshes into a large gear 8, journaled in suitable boxes

45 9. This gear is connected by a bar 10 to a similar gear-wheel 11, also journaled in suitable boxes 12. The gear 11 meshes into a smaller gear 13, which drives a shaft 14, running longitudinally and centrally through the whole 50 length of the vat. This shaft is supplied with a

series of stirring-forks 15, arranged as shown in plan, Fig. 2, and section, Fig. 4. The vat is divided longitudinally into sections separated by perforated cross-partitions 16, rising above the level of the dye liquor. The forks extend 55 from the shaft as near the bottom of the vat as practicable and operate freely between the sections. A water-pipe 17 supplies water, and a steam-pipe 8, arranged along one side of the vat, introduces steam through the curved pipes 60 19 into the bottom of each section. An outlet-pipe 20 discharges the liquid contents of the entire vat. A cover 21 incloses the top, having a hinged door 22 at one side, and an outlet-flue 23 carries off the steam and fumes. By the 65 arrangement of the gears, the pinion-gear 7 being very small, a slow gentle motion is communicated to the stirring-fingers 15, and by the adjustment of the connecting-bar between the gears 8 and 11 this motion is made 70 reciprocating, the same as hand-stirring with a fork or pole. The gear 8 has one spoke provided with a series of bolt-holes 24. (See Fig. 3.) If the bar 10 is bolted near the center of the gear, its radius is so short that its rotary 75 motion will communicate a reciprocatory motion to the gear 11. Where the connecting-bar is bolted near the periphery, this motion can be adjustably lengthened, so as to raise the materials being dyed at each side alternately 80 above the dye liquor, where they are suspended while the bar 10 is crossing the center of gear 8. The motion being slow, this period of suspension is sufficient to let the materials absorb the dye, which they do better when so 85 lifted into the atmosphere than if they are at all times simply stirred below the surface of the liquor. The connecting-bar 10 can also be so adjusted as to make the motion of the stirring-fingers a complete rotary motion, 90 which under some circumstances is desirable.

Having thus described my invention, what I claim, and desire to secure by Letters Patent, is—

1. In an automatic dyeing apparatus, the 95 combination of a vat adapted to hold dye liquor, perforated partitions separating said vat into cross-sections, a longitudinal shaft passing through said partitions, and forks arranged upon said shaft operating between 100

said partitions substantially as described and shown

2. In an automatic dyeing apparatus the combination of a vat adapted to hold dye liquor, perforated partitions dividing said vat into cross-sections, a longitudinal shaft through the vat, stirring-forks arranged between said partitions radiating from said shaft, and mechanism operating said shaft to 5 raise the materials being dyed upon said forks, suspending them above the liquor an appreciable time whereby the dye is absorbed into the fabric, lowering the materials and stirring them through the liquor, raising them at the 10 opposite side, an appreciable suspension, and automatically repeating the process by a reciprocatory movement substantially as described and shown.
3. In an automatic dyeing apparatus the 15 combination of a vat adapted to hold dye liquor, perforated cross-partitions dividing said vat into sections, through which the dye liquor flows and wherein different materials to be dyed may be arranged to be dyed in the 20 one operation, a longitudinal shaft passing through said partitions, and forks operating in each section to stir and raise the materials with a reciprocatory movement substantially 25 as described and shown.
4. In an automatic dyeing apparatus the 30 combination of a vat adapted to hold dye liquor, perforated partitions dividing said vat into cross-sections a longitudinal shaft carrying radiating forks operating between said sections arranged in said vat, means to give a re-

ciprocatory movement to said shaft, and means to limit the extent of said movement substantially as described and shown.

5. In a dyeing apparatus the combination of an inclosed vat adapted to hold dye liquor, 40 perforated partitions dividing said vat into cross-sections, means for stirring the materials to be dyed automatically within said inclosure actuated and controlled from without, steam and water admission conduits controlled from 45 without, and a vent to said inclosure for carrying away the vapors arising from the dye liquor, substantially as described and shown.

6. In an automatic dyeing apparatus the combination of a vat adapted to hold dye 50 liquor, perforated partitions dividing said vat into cross-sections, a longitudinal shaft through the vat, stirring-forks operating between said partitions radiating from said shaft, and mechanism operating said shaft to 55 raise the materials being dyed upon said forks, rotating them slowly above the liquor an appreciable time whereby the dye is absorbed into the fabric, lowering them gently at the opposite side, and stirring them through the 60 dye liquor by a slow rotary motion substantially as described and shown.

In testimony whereof I have signed my name to this specification in the presence of two subscribing witnesses.

JAMES MARSHALL.
